DUAL CIRCUIT SIGNAL CONTROL

Henry T. Chapek and Heard S. Lowry, Jr., Manchester, Tenn., assignors to the United States of America as represented by the Secretary of the Air Force

Application December 1, 1955, Serial No. 550,508

4 Claims. (Cl. 235—92)

This invention relates to computing, and particularly to computing circuitry utilizing successions of computing elements, each including signal read-out and indicating facilities.

A feature of the invention is the provision of novel resetting facilities permitting interruption of the normal trend of signal transfer (e. g. digital computing) at any stage of a complete cycle, by means operating to modify the potential characteristics of the signal transfer elements themselves.

The invention is illustrated as incorporated in signal transfer elements of the Eccles-Jordan type trigger amplifier. The action of this two-tube circuit depends upon the fact that current flows through only one tube at a time. This form of multivibrator employs direct coupling between the anodes and grids of the two tubes. It is a circuit possessing two conditions of stable equilibrium. One condition is when tube 1 is conducting and tube 2 is cut-off; the other when tube 2 is conducting and tube 1 is cut-off. The circuit remains in one or the other of these two conditions, until some action occurs which causes the nonconducting tube to conduct. The tubes then reverse their functions and remain in the new condition as long as no plate current flows in the cut-off tube. Because of this sudden reversal or "flopping" from one state of equilibrium to the other, this type of circuit is referred to as a "flip-flop" circuit.

The "flip-flop" circuits are arranged serially to form a counting or analogous signal transfer system. Means are provided so that the same tube in each of the "flip-flop" circuits always conducts in the null position. One method is to drive the desired tube to the conducting state in preparation for counting. The counting circuit then receives information in the form of repeated pulses, the number of repetitions imparting the desired information. These pulses actuate some or all of the "flip-flop" circuits which are arranged serially. It would be desirable to have some visual indication of the state of each of the "flip-flop" circuits in the counting system and simultaneously a completely independent output to any external device.

After a train of pulses into the counter, the visual indication for each of the "flip-flop" circuits will then show whether or not they are in a null condition. If not, means are provided to reset the "flip-flop" circuits to the null condition in preparation for another counting cycle.

One object of the invention is to provide a visual indication of the state of the "flip-flop."

Another utilization is to provide a simultaneous contact output from the "flip-flop" circuit which is completely independent and which does not require the addition of cathode followers or relay pullers. Another object of this invention is to provide a means for resetting the "flip-flop" circuits simultaneously effective upon all units of the computing chain.

Still further objects and advantages of the invention will be apparent in the following description and claims con-

sidered with the accompanying drawing showing a schematic wiring diagram embodying the invention.

Referring to the drawing, Fig. 1, there are shown successive computing elements connected serially. Each one of the elements are identical and each element is a modified type Eccles-Jordan "flip-flop" circuit. This "flip-flop" circuit is comprised of two triode vacuum tubes 2 and 3. Each of the triodes 2 and 3 are adapted to receive an actuating input pulse from common input terminal 39. 5 This input pulse is impressed upon the grid 4 of tube 2 through capacitor 6 and upon the grid 5 of tube 3 through capacitor 7. Each tube is provided with a grid resistor to ground, 8 for tube 2 and 9 for tube 3. The cathode of tube 2 is provided with resistor 14 to ground. Cathode 13 10 of tube 3 is provided with divided resistors comprising resistor 14 and resistor 13 which is normally shunted by switch 17. Cathode resistor 14 is common to tubes 2 and 3. Cathode resistor 14 is by-passed to ground by capacitor 16. Resistor 18 in shunt with capacitor 20 couples 15 the anode 10 of tube 2 to grid 5 of tube 3. Resistor 19 is in shunt with capacitor 21 couples the anode of tube 3 to grid 4 of tube 2. The anode of tube 2 is loaded by a series connected resistor which is divided into resistors 22 and 26. The output of the "flip-flop" circuit 1 is taken 20 from point 28 between resistors 22 and 26. This output is adapted to feed the next succeeding "flip-flop" circuit. Anode 11 of tube 3 is loaded by series connected resistor 23 and inductance 25. Inductance 25, an energizing coil 25 of relay 40, is shunted by diode 27. Single pole-double throw switch 29 is actuated by inductance 25. There are 30 two voltage sources 34 at -75 volts and 33 at +25 volts. Connected in series between 33 and 34 are resistors 31, 32 and one side 36 of switch 29. In shunt with resistor 32 and voltage source 33 is neon tube 30. The other side 35 of switch 29 is the output line 38 to output connection 35.

With the "flip-flop" circuit in the null position (i. e. at rest) tube 2 is conducting and tube 3 is nonconducting. 40 Relay 40 is not energized so that single throw-double pole switch 29 connects resistors 31 and 32 to point 36 and then across voltage sources 33 and 34 thus forming a voltage dividing network. Neon tube 30 is in shunt with only a part of this voltage dividing network and receives an inadequate voltage to ionize it. With tube 2 conducting 45 and tube 3 nonconducting, one method to actuate the "flip-flop" circuit is to apply a negative pulse to the common input 39. This will decrease the grid potential of tube 2. The plate potential of tube 2 rises sharply, carrying with it the grid potential of tube 3, thus allowing tube 50 3 to conduct. The accompanying decrease in plate potential of tube 3 forces the grid potential of tube 2 below cut-off. Tube 3 remains in a conducting state and tube 2 remains in a nonconducting state.

When tube 3 is in a conducting state and tube 2 is nonconducting, relay 40 is energized by reason of the current flow through inductance 25. Diode 27 damps the transients through inductance 25. The series resistor 23 isolates the capacity to ground of inductance 25, thus preventing this capacity to ground from effecting the action 60 of the "flip-flop." Resistor 23 also allows compensation for different ohmic values of relay inductance.

The inductance 25 being in an energized state, single pole-double throw switch 29 is actuated and switch 29 is shifted from contact 36 to 37. Neon tube 30 is now 65 connected in series with resistor 32 and both are across voltage sources 33 and 34. There is adequate voltage to ionize neon tube 30 which glows. This serves as a visual indication of the state of the "flip-flop." Simultaneously line 38 provides a contact output directly to terminal 35. This may also serve as a convenient means for reading 70 out the state of the counter without disturbing the count.

At any stage of a counting cycle or at its completion, it may be desirable or necessary to re-set the "flip-flop" in the computing chain to a null or rest condition, thereby requiring all of tubes 2 to revert to a conducting condition and tubes 3 to a nonconducting one. A resetting pulse is provided from source 55. This will energize series connected relays 41 to 54. The description of operation in "flip-flop" 1 is representative of all. Switch 17 shunting resistor 15 will open and thereby will provide tube 3 with divided cathode resistors 14 and 15. Where tube 3 is in a conducting state, the bias on tube 3 will increase in a negative direction. The plate potential of tube 3 rises, carrying with it the grid potential of tube 2 thus allowing tube 2 to conduct. The accompanying decrease in plate potential of tube 2 forces the grid potential of tube 3 below cut-off. Tube 2 remains in a conducting state and tube 3 remains in a nonconducting state. Switch 17 again shunts resistor 15. "Flip-flop" 1 is now in a standby condition available for another counting cycle.

What is claimed is:

1. A computing system comprising a succession of two-state devices each of which includes a pair of anode circuits, a pair of cathode circuits, and a pair of excitation grid circuits, means for transferring signals from each of said two-state devices to the next succeeding two-state device, relay-operated switch means in each of said cathode circuits, and means controlled by said switch means for modifying the potential characteristics of the signal transfer means and thereby controlling the signal transferring operations.

2. A computing system as defined in claim 1, wherein the means for modifying the potential characteristics of the signal transfer means comprises a bridging circuit coupling the cathode circuits of each of the said two-state devices, said bridging circuit being of predetermined resistance value, and wherein said relay-operated switch means establishes a conductive path shunting said bridging circuit.

3. A computing system comprising a succession of two-state devices each of which is comprised of two tubes of the triode type employing cross-coupling between the plates and grids of the said tubes, switch operating relay means in the plate circuits of one tube of each of the said two-state devices, means responsive to the operation of each of the said two-state devices to energize said relay means and thereby control the signal output from each of the said two-state devices and including a neon tube type indicating element, and a voltage dividing network in circuit with said neon tube, said relay, switch and network cooperating to provide a direct output from said two-state device.

4. A computing system comprising a succession of two-state devices each of which is comprised of two tubes of the triode type employing cross-coupling between the plates and grids of the said tubes, switch operating relay means in the plate circuits of one tube of each of the said two-state devices, means responsive to the operation of each of the said two-state devices to energize said relay means and thereby control the signal output from each of the said two-state devices and including a neon tube type indicating element, and a voltage dividing network in circuit with said neon tube, said relay, switch and network cooperating to provide a direct output from the said two-state device, simultaneously with the flashing of said neon tube.
